(57) CLAIM

The ornamental design for a shark mouth hoodie, as shown and described.

DESCRIPTION

FIG. 1 is a front perspective view showing the shark mouth hoodie;

FIG. 2 is a front view showing the shark mouth hoodie;

FIG. 3 is a rear view showing the shark mouth hoodie;

FIG. 4 is a right side view showing the shark mouth hoodie;

FIG. 5 is a left side view showing the shark mouth hoodie;

FIG. 6 is a top view showing the shark mouth hoodie;

FIG. 7 is a bottom view showing the shark mouth hoodie;

and,

FIG. 8 is a front view of the shark mouth hoodie showing the environment in which it is used.

In the drawings, the broken lines illustrate portions of the shark mouth hoodie that form no part of the claimed design; the additional broken lines shown in FIG. 8 illustrate environmental subject matter only and form no part thereof. The shark mouth forming part of the claimed design is a registered trademark of Spray Moret, LLC.

1 Claim, 7 Drawing Sheets
